Patented Nov. 4, 1975

237,535

FLOATING POLLUTANT SKIMMER

Douglas J. Graham, 19 Imperial Ave.,
San Francisco, Calif. 94123

Filed May 6, 1974, Ser. No. 467,063

Term of patent 14 years

Int. Cl. D15—99

U.S. Cl. D49—11

FIG.—1

FIG.—2

FIG.—3

FIG.—4

FIG.—5

FIG. 1 is a side elevational view of a floating pollutant skimmer embodying my new design, the opposite side being a mirror image thereof;

FIG. 2 is a top plan view thereof;

FIG. 3 is a front elevational view thereof;

FIG. 4 is a bottom plan view thereof; and

FIG. 5 is a rear elevational view thereof.

I claim:

The ornamental design for a floating pollutant skimmer, as shown and described.
